REVOLVING CAM ELECTRICAL SWITCHES
Henry George Rossini, Scotia, N.Y., and Samuel Paul
Jones, Erie, Pa., assignors to General Electric Com-
pany, a corporation of New York

Filed Feb. 28, 1966, Ser. No. 530,266
12 Claims. (Cl. 200—166)

This invention relates to revolving cam electrical switches and more particularly to a new and improved cam arrangement therefor to provide electrical switches of such type which are especially adapted for high voltage applications.

While the cam arrangements of this invention have utility in a wide variety of switching apparatus, they are especially suited for use in railway vehicle circuit controllers and will be particularly described in that connection. The use and operation of circuit controllers of such type are described in U.S. Patents Nos. 2,566,898 and 3,034,031, for example.

Electrical circuit controllers for use in rail rapid transit equipment, for example, are usually reversible motor-driven revolving-cam electrical switches having a plurality of switch positions to control motor-power switching for series-parallel operation of the vehicle traction motors as well as to provide for coasting and braking. In such switches a plurality of cams and appropriate cam spacers constructed of an electrically insulating material are arranged on a camshaft of steel or the like to be driven thereby so that engagement of the cams with the actuating means of appropriate switch means or contactors causes operation of such devices in a desired sequence. The contacts of such devices are usually made from an electrically conductive material, such as copper. Often, a large potential difference may exist between adjacent contactors so that it is necessary that such contactors be electrically isolated from each other. For many applications, this can be satisfactorily accomplished by merely providing cams and cam spacers of a suitable electrically insulating material. Because of the relative movement of the switch parts on each other when actuated by the cams, particles of electrically conductive material, usually particles of copper from the contacts, tends to coat the side surfaces of the cams with a film which is electrically conductive. This condition is aggravated when the electrical switch is operated in a dirty, oily or otherwise contaminated environment. Under such operating conditions the oil or other contaminants may mix with the conductive dust to form an electrically conductive fluid which tends to creep down the side surfaces of the cam toward the cam shaft. Since in the vast majority of applications the camshaft is at ground potential, this conductive fluid may establish a conductive path between the electrical contacts and ground through the camshaft to result in possible damage to the equipment and certain disruption in operation of the circuits being controlled.

Prior art attempts to overcome this difficulty such as by the provision of larger diameter cams, tightly pressing adjacent cams and/or cam spacers together or attempting to hold closer manufacturing tolerances have not been entirely satisfactory, especially for switches for the higher voltage applications. None of the prior art arrangements of which we are aware capable of utilizing individual cam elements have been capable of positively preventing the eventual establishment of such an electrically conducting path.

Therefore, it is an object of this invention to provide a new and improved cam arrangement for revolving-cam electrical switches which overcomes one or more of the foregoing prior art difficulties and is capable of operation at much higher voltages.

2

It is another object of this invention to provide a new and improved cam arrangement for a revolving-cam electrical switch which inherently and positively prevents establishment of an electrically conductive path to the cam-shaft between adjacent cams.

Briefly these objects are obtained in a cam arrangement wherein a positive sealing means is provided between adjacent cam element faces which effectively blocks creepage of conductive media down the cam element face to the shaft thereby preventing short circuits and concurrent damage to equipment.

As used throughout the specification and in the appended claims the term "cam element" is intended to include cams as well as any spacers which may be disposed adjacent thereto.

The subject matter which is regarded as our invention is particularly pointed out and distinctly claimed in the appended claims. Our invention, however, both as to its organization and method of operation, together with further objects and advantages thereof, is best understood with reference to the following description taken in conjunction with the accompanying drawings in which:

FIGURE 1 is a cross section view of a cam arrangement according to one form of the present invention, and

FIGURES 2 and 3 are cross section views of cam arrangements according to another form of this invention.

Referring now to FIGURE 1 according to one form of this invention a camshaft 1 is illustrated having a plurality of cam elements thereon. As shown the arrangement includes four arbitrarily placed cams 2, 3, 4, and 5, and three cam spacers 6, 7 and 8 separating the cams 4 and 5. Although only cams 4 and 5 are shown separated by spacers, it will be understood that for some applications all of the cams may be arranged with such spacers therebetween. The cams and cam spacers are preferably comprised of an electrically nonconductive material. In order to insure that the camshaft is strong enough for high voltage and high mechanical stress applications such as in railway vehicle controllers, the camshaft 1 is preferably comprised of a strong rigid material such as steel. The sides or faces of the cam elements may include ripples 9, illustrated on the face of the cam 2 only, to increase the length of the creepage path between the cam surface and the central area of the cam near the shaft. The external surface of the cam spacers 6 through 8 may be made preferably large by extending the spacers radially to increase the creepage path between the adjacent cam elements.

The shaft 1 may be square so as to snugly fit into square star-shaped or otherwise matching holes provided in the central portions of the cams. In an alternate arrangement the shaft and holes in the cams may be round and a keying means may be provided in order to secure the cam to the shaft for rotation. It is desirable to maintain close tolerances between the holes of the cam elements and the camshaft in order to prevent creepage along the camshaft. It will be seen, however, that by means of the present invention the requirement for such close tolerances is not as strict as in previous camming arrangements since this invention precludes creepage of conductive fluid to the camshaft. Moreover, since the spacers are not required to actuate any switch element, they need not be drivingly connected to the shaft.

The central portions of the cams 2 through 5 are provided with extension members or projections adapted to interlock with each other when the cams are placed in adjacent relationship. Taking the adjacent cams 2 and 3 as representative, cam 2 is shown to include an outer projection member 10 and an inner projection member 11 while the cam 3 is shown to include a center projection member 12 which, when the cams are placed on the shaft adjacent to each other in operating position, is disposed

between the projection members 10 and 11. The outer projection member 10 is shown in contacting relationship with the face of the cam 3. The projection inner member 11 is disposed in noncontacting relationship with the face of the cam 3 so that a cavity 13 is formed between the lower surface of the projection member 12, the side surface of the projection member 11, the face surface of the cam 3, and the camshaft 1. In a like manner, the projection member 12 is spaced away from the face of the cam 2 to form a cavity 14.

The interior faces of the two adjacent cams 3 and 4 are similarly constructed in an interlocking fashion. Thus an outer projection member 15 and an inner projection member 16 of the cam 3 interlock with a central projection member 17 provided on the cam 4. The interlocking nature of these two cams are such that the cavity 18 is formed adjacent to camshaft 1 and a cavity 19 is formed adjacent the central projection member 17.

The three spaced members 6, 7, and 8 between the cams 4 and 5 are shown with interlocking projection members which engage each other in contacting relationship. The hollow cores of the cam spacers are dimensioned so as to form a cavity 29 when assembled on the camshaft 1. An outer projection member 20 and an inner projection member 21 of the cam 4 interlock with a central projection member 22 of the cam spacer 6 to form a cavity 23 adjacent the side surface of the projection member 22. A central projection member 24 of the cam 5 interlocks with an outer projection member 25 of the cam spacer 8 in contacting relationship. The lower surface of the projection member 24 and the side surface of the cam 5 form the upper-right and right boundaries for the cavity 29. As may be seen the cam spacers are held in assembled position away from the camshaft by virtue of the support provided by the projection member 21 of cam 4 and the projection member 24 of cam 5.

At the left end of the camshaft 1 as shown in FIGURE 1 a plug member 26 is shown in interlocking engagement with the cam 2 and a similar plug member 27 is shown at the right end of the camshaft 1 in interlocking engagement with the cam 5. The extensions of the camshaft 1 beyond either the plug members 26 or the plug member 27 may engage with bearings or a camshaft driving means which, for simplicity, is not shown.

From an inspection of FIGURE 1 and with reference to the above description it is apparent that the general scheme of the cams, cam spacers, and the camshaft provides the formation of interior cavities as illustrated by the cavities 13, 18, and 29 adjacent the camshaft 1, and center cavities 14, 19, and 23, adjacent the side surfaces of the central projection members 12, 17, and 22. Each interior cavity such as 13 has associated therewith a central cavity member such as 14 disposed to its left and positioned away from the camshaft 1 such that communication between the associated cavities exists only between the contacting junction between the central projection member of the right hand cam element and the inner projection member of the left hand cam element. It will be apparent that additional cam and cam spacers than those shown in FIGURE 1 may be employed by positioning them along the camshaft 1 as required and that their projection members and cavity arrangements will be substantially similar to those shown.

In a preferred embodiment of the species shown in FIGURE 1, the cavities are filled with an insulating sealant, such as silicone rubber, silicone grease or other suitable electrical insulating composition. The sealant may be in liquid form when it is poured into the cavities during the manufacture of the camming arrangement. After the manufacture is completed, however, the sealant material may remain a liquid or it may harden. In either case, however, the sealant forms a positive seal thereby blocking creepage down the faces of the cam elements.

When a hardening type sealant is employed, the interlocking nature of the cams and cam spacers and the hard-

ened sealant in the cavities formed between the interlocking elements tend to add stiffness to the camshaft 1 which is extremely desirable when greater pressures are required between the cams and the switching means (not shown) being actuated, which conditions may often occur in the electrical control of railway vehicle equipment.

In a preferred method of making the camshaft and camming arrangement as shown in FIGURE 1, the right end of the camshaft 1 including the plug 27 is positioned downwardly so that the camshaft 1 extends upward from that end. The plug 27 is inserted over the camshaft 1 and is slid down the camshaft until it reaches its desired position on the shaft as shown in FIGURE 1. The plug 27 is then secured to the camshaft 1 at this position by any suitable means. Next the cam 5 is slid onto the shaft followed by the spacers 8, 7 and 6 in that order so that the three sides of the cavity 29 are formed with the fourth and open side being at the top. The sealant material, which may be in liquid form at this time, is then poured into this cavity until it is substantially filled. Next the cam 4 is slid down the camshaft 1 until it begins to interlock with the spacer 6. As the interior projection member 21 of the cam 4 enters the cavity 29, it will begin to displace a portion of the liquid sealant material equal to the volume of that portion of the projection member 21 that is inserted into the cavity 29. The liquid sealant material thus displaced is forced between the projection member 21 and the projection member 22 into the center cavity 23. The volume of the center cavity 23 is chosen to be almost equal to or slightly greater than the volume of the sealant material displaced therein so that all, or at least most all of the volume of the cavity 23 becomes filled with the sealant when the cam 4 is firmly in place. In assembling the cam spacers and cams in the manner described, a small portion of the sealant material may become forced between contacting surface of the cam spacers and between contacting surfaces of the cams. This, however, does not detract from the effectiveness of the assembly but rather further insures that the creepage path of the conductive dust is effectively sealed off. The rest of the camshaft assembly is made in a similar manner as described until the entire assembly is completed. The upper end of the camshaft 1 is then terminated with the plug 26. In order to insure that the seal formed between adjacent cam members and between the exterior portions of the cam and the camshaft 1 is maintained effective, it is necessary that no voids or open spaces form between the sealant material and the boundary surfaces of the internal cavities. Thus, the sealant material should be chosen such that as it hardens it does not contact excessively. Also, it is desirable that the sealant does not crack as it hardens but rather remains relatively flexible. Silicone rubber and epoxy resin materials have been found to be particularly suitable for this purpose.

In FIGURE 2 there is illustrated a portion of a cam arrangement for a revolving cam electric switch constructed in accordance with another embodiment of the invention. As shown, the required positive seal between adjacent cam elements for blocking the formation of an electrical creepage path to the shaft 1 is provided by one or more resilient members 30 of a suitable electrically material.

To this end each of the cam elements shown as cams 32, 33 and 34 are provided with one or more annular grooves 36 in the opposite sides thereof. The grooves are so arranged that grooves of adjacent cams or spacers register with each other to form an annular cavity between adjacent cam elements. The resilient member 30 is dimensioned so that it will be tightly retained within the annular cavity to effect the positive seal between adjacent cam elements. Conveniently, resilient member 30 may be a seal of the well known O-ring type. When such O-ring type seal is employed tight compression thereof in the annular cavity thereof may be provided by select-

ing an O-ring type seal having an inside and an outside diameter which are slightly larger than inside and outside diameters of the annular cavity.

In the embodiment illustrated in FIGURE 3 the cam elements are shown as being of the interlocking type with the resilient member 30 providing the required seal as in the arrangement of FIGURE 2. As shown, one or more such resilient members 30 may be employed and may be located as in FIGURE 2 in the cavity formed by registering grooves in the sides of adjacent cam elements, or in the cavity formed by registering grooves in the interlocking portions of the cam elements. Again, the resilient member 30 may be an O-ring type seal.

Although for purposes of illustration several resilient members 30 are shown interposed in the cavities formed between adjacent cam elements, one such member is all that is required for most applications. Resilient O-ring seals are well known and are commercially available in a wide variety of sizes and cross sectional diameters as well as of various materials the selection of which will depend to some extent upon the expected operating environment of the switch.

Since member 30 is retained tightly, and preferably compressed, in the annular cavity formed between adjacent cam elements and since it is also resilient, it provides a positive seal between adjacent cam elements in spite of shrinkage or other aging effects of the cam elements. Although not illustrated, it is often desirable to provide a coil spring means at one end of the cam element assembly to urge the elements together to minimize the effects of shrinkage or aging of the cam elements.

From the foregoing description it is apparent that the arrangement of this invention allows for the use of individual cam elements which may be arranged in adjacent order to provide a variety of different switching arrangements with ease of repair, replacement or rearrangement of cam elements while at the same time providing for a positive seal between adjacent cam elements to prevent establishment of a conducting path between the switch being actuated and the shaft upon which the cam elements are mounted.

While the camshaft assembly and method for making the same are described in terms of a preferred embodiment, it should be understood that various modifications and arrangements and other methods will be obvious to those skilled in the art. Thus, it is not intended that applicant be limited to the embodiments described but rather should be entitled to the full scope of the appended claims.

What we claim as new and desire to secure by Letters Patent of the United States is:

1. A camming arrangement for an electrical controller comprising:

- (a) a camshaft;
- (b) a plurality of cams fixedly secured to said camshaft for rotation therewith; and
- (c) sealing means between each set of adjacent cam elements positioned intermediate said camshaft and the outer portions of said cam elements, said sealing means effectively blocking the formation of an electrical creepage path between said outer portions and said camshaft.

2. A camming arrangement for an electrical controller for reducing the creepage of conductive dust comprising:

- (a) a camshaft;
- (b) a plurality of cams fixedly secured to said camshaft for rotation therewith;
- (c) said cams including projections so that adjacent cams interlock with each other by means of said projections;
- (d) said interlocked projections forming cavities in the creepage path of the conductive dust; and
- (e) a sealant disposed in said cavities.

3. The camming arrangement as defined in claim 2 wherein said interlocked projections of any pair of adjacent cams form a first and second cavity, both of said cavities being in the creepage path of the conductive dust.

4. The camming arrangement as defined in claim 3 wherein said first and second cavities are axially displaced from each other but communicate with each other through a junction between a pair of said interlocking projections.

5. The camming arrangement as defined in claim 4 wherein a first one of said pair of interlocking projections is disposed within said first cavity so as to displace a volume approximately equal to the volume of said second cavity.

6. The camming arrangement as defined in claim 3 wherein said sealant comprises silicone rubber.

7. A camming arrangement for an electrical controller for reducing creepage of conductive dust comprising:

- (a) a camshaft;
- (b) a plurality of cams fixedly secured to said camshaft for rotation therewith;
- (c) a plurality of cam spacers positioned on said cam-shaft spacing said cams at desired distances;
- (d) said cams and said cam spacers including projections so that adjacent cams, adjacent cam spacers, and adjacent cams and cam spacers interlock with each other by means of said projections;
- (e) said interlocking projections between adjacent cams and between adjacent cams and cam spacers forming cavities in the creepage path of the conductive dust; and
- (f) a sealant material disposed in said cavities.

8. A camming arrangement as defined in claim 7 wherein in said interlocking projections of any pair of adjacent cams and any adjacent cams and cam spacers form a first and second cavity, both of said cavities being in the creepage path of the conductive dust.

9. The camming arrangement as defined in claim 8 wherein said first and second cavities are axially displaced from each other but communicate with each other through a junction between a pair of said interlocking projections.

10. The camming arrangement as defined in claim 9 wherein a first one of said pair of interlocking projections is disposed within said first cavity so as to displace a volume approximately equal to the volume of said second cavity.

11. In a revolving cam electrical switch, the combination comprising:

- (a) a shaft having a plurality of electrically nonconducting cam elements arranged thereon for rotation with said shaft, each of said cam elements having at least one annular groove in the opposite sides thereof adapted to register with the similar groove of an adjacent cam element to form an annular cavity between said adjacent cam elements; and
- (b) a resilient member of electrically insulating material retained tightly in said annular cavity and operative to provide a positive annular seal between adjacent cam elements.

12. The revolving cam electrical switch as recited in claim 11 wherein said resilient member is an O-ring type seal and the inside and outside diameters of which are slightly greater than those of said annular cavity so that said seal is compressed tightly within said cavity.
